CLAIM

We claim the ornamental design for a lid for a canning jar, as shown and described.

DESCRIPTION

FIG. 1 is a perspective view of a lid for a canning jar. FIG. 2 is a top view of the lid for a canning jar of FIG. 1. FIG. 3 is a bottom view of the lid for a canning jar of FIG. 1.

FIG. 4 is a right side view of the lid for a canning jar with the left side view being a mirror image;

FIG. 5 is a front view of the lid for a canning jar of FIG. 1.

FIG. 6 is a back view of the lid for a canning jar of FIG. 1.

FIG. 7 is a perspective view of the lid for a canning jar of FIG. 1 depicting the lid as used on a canning jar.

FIG. 8 is a perspective view of a lid for a canning jar according to a second embodiment.

FIG. 9 is a top view of the lid for a canning jar of FIG. 8.

FIG. 10 is a bottom view of the lid for a canning jar of FIG. 8.

FIG. 11 is a right side view of the lid for a canning jar with the left side view being a mirror image;

FIG. 12 is a front view of the lid for a canning jar of FIG. 8.

FIG. 13 is a front view of the lid for a canning jar of FIG. 8; and,

FIG. 14 is a perspective view of the lid for a canning jar of FIG. 8 depicting the lid as used on a canning jar.

In the drawings, the broken lines show portions of a lid and jar that form no part of the claim.

1 Claim, 10 Drawing Sheets
